BY Wm. W. L.

ATTORNEY

UNITED STATES PATENT OFFICE.

FRANKLIN E. ROBERTS, OF FLINT, MICHIGAN.

COMBINED TRY-SQUARE AND PROTRACTOR.

SPECIFICATION forming part of Letters Patent No. 425,698, dated April 15, 1890.

Application filed August 2, 1889. Serial No. 319,541. (No model.)

To all whom it may concern:

Be it known that I, FRANKLIN E. ROBERTS, of Flint, in the county of Genesee and State of Michigan, have invented certain new and 5 useful Improvements in Combined Try-Squares and Protractors, of which the following is a specification, reference being had to the accompanying drawings, in which—

Figure 1 is a perspective view of my improvement. Fig. 2 is a horizontal section on the line 2 2, Fig. 1. Fig. 3 is a cross-section of the same on the line 3 3, Fig. 1.

The object of the invention is to provide an instrument by which operators or workmen 15 in the various trades or arts may readily determine various angles and lay out work.

The invention will be first described and then specifically claimed.

A represents the frame of the instrument, 20 consisting in an outer section B, formed of two approximately triangular or quadrant-shaped wings b b at right angles to each other, and an inner section C, formed of two similar wings c c. The edges D of the frame are 25 straight and at right angles to each other and form the try-square; said edges being graduated on the outer faces of all four wings b b c c into inches and fractions thereof. The several wings may be provided with register- 30 ing openings d, if desired, in order to lighten the instrument. The angular space between the ends e of the frame is provided with a filling and spacing piece E, held therein by screws f flush with the faces of the several wings. 35 This piece E spaces the two frame-sections BC. In the spaces thus formed are placed two quadrants F F, which are each provided with a curved slot g concentric with the curved edges m. Concentric with these slots g are formed 40 three series of radial graduations h i j, the graduations of the inner series each representing ten degrees of radiation, the second five degrees each, and the outer or third two and one-half degrees each.

45 The edges a of the wings b b c c are curved to register with the curved edges of the quadrants, and the latter are each provided with a thumb or finger projection n, by which they may be moved in or out.

50 G are set-screws passing through the try-square portions of the frame A and the slots

g, the heads of the screws being nicked and countersunk, so as to be flush with the frame.

It will be seen from the above that the quadrants may be moved wholly within the frame 55 in order that the straight edges D thereof may be used as a try-square, and that by pressing the finger projection n outward any one of the radial graduations may be brought into line with the straight edge, when an angle 60 may be marked on the work. By tightening the screw the quadrant will be firmly clamped between the two wings.

The instrument may be placed in the angle 65 of a box or room when it is necessary to find out what such an angle may be, and if it is found to be greater than a right angle a quadrant may be moved outwardly and the exact angle determined.

The instrument is capable of many and va- 70 ried uses by carpenters, millwrights, cabinet-makers, car-builders, and draftsmen, and it may be made of sheet or other metal, wood, or compressed pulp.

In practice I have found that it is not es- 75 sential to place figures or other marks upon the quadrant graduators; but in some instances I propose to do so, and they may of course be varied indefinitely.

Having thus described my invention, what I 80 claim, and desire to secure by Letters Patent, is—

1. A combined try-square and protractor consisting in a try-square having separate and independent quadrants movably secured 85 to its two members and adapted to be projected beyond the edges thereof, substantially as set forth.

2. A combined try-square and protractor consisting in a try-square and quadrants pro- 90 vided with concentric slots and set-screws for clamping the quadrants in any desired position on the members of the try-square, sub- stantially as set forth.

3. A combined try-square and protractor 95 consisting in a try-square having quadrants adjustably secured to its members and each provided with concentric series of radial graduations, substantially as set forth.

4. A combined try-square and protractor 100 consisting in a frame formed of inner and outer spaced sections, each formed of two

wings at right angles to each other to form the try-square, and a protractor adjustable between each pair of wings, substantially as set forth.

5. A combined try-square and protractor consisting in a frame formed of inner and outer spaced sections, each having two wings at right angles to each other registering at their straight edges and forming the try-square, the quadrants in the spaces between said wings, and set-screws for clamping the quadrants in their adjusted positions, substantially as set forth.

6. A combined try-square and quadrant consisting in a frame formed of inner and outer spaced sections, each having two quadrant-shaped wings at right angles to each other with their straight edges registering, the quadrants in the spaces between the said wings, and having finger projections on their

curved edges projecting beyond the curved edges of the wings, substantially as described.

7. A combined square and quadrant consisting in a frame formed of separate and independent inner and outer sections, each having two wings at right angles to each other registering at their straight edges, an angular spacing-piece between the two sections, screws or rivets passing through said sections and spacing-piece, quadrants within the spaces between the wings and provided with curved slots, radial graduations, and finger projections on their curved edges extending beyond the curved edges of the frame, and set-screws passed through the frame-sections and the slots, substantially as set forth.

FRANKLIN E. ROBERTS.
